UNITED STATES PATENT OFFICE.

EDWARD S. CORY, OF BIG RAPIDS, MICHIGAN, ASSIGNOR OF ONE-HALF TO
HERBERT M. REYNOLDS, OF SAME PLACE.

SASH-FASTENER.

SPECIFICATION forming part of Letters Patent No. 341,557, dated May 11, 1886.

Application filed July 6, 1885. Serial No. 170,812. (No model.)

To all whom it may concern:

Be it known that I, EDWARD S. CORY, a citizen of the United States, and a resident of the city of Big Rapids, in the county of Mecosta and State of Michigan, have invented 5 a new and useful Window-Sash Holder and Lock, of which the following is a specification.

My invention relates to a window-sash fastener and lock having a revolving bolt; and the object of my invention is to hold and lock the window-sash in any required position, the bolt acting both as a lock and as a sash-holder, as fully described below. This object I accomplish by means of the mechanism 15 illustrated in the accompanying drawings, in which—

Figure 1 is a plan view of my invention, with a section of the window-frame with 20 catches thereon, showing the window-sash locked. Fig. 2 is a perspective view of the bolt detached. Fig. 3 is a plan view of the device with the bolt turned so as to hold and lock the sash up. Fig. 4 is an end view of 25 the window-sash holder. Fig. 5 is a reverse view of the part shown in Fig. 1, and Fig. 6 is a plan view of the device with the bolt turned so as to lock the window-sash down.

Similar letters refer to similar parts throughout the several views.

In the drawings, A A represent the metallic case or shell which holds the locking-bolt, and for strength, cheapness, and durability I make it of one piece of metal.

35 H represents the end of the lock-bolt which comes in contact with the stop or catch.

G represents the lock-bolt, having the head or enlarged portion H. In the head H is a bevel-groove.

40 J shows the bottom of the bevel-groove, and I the flaring sides.

One end of the coil-spring M rests against the shoulder formed by the head H, and the other end of the coil-spring presses against 45 the shell or case A, so that the bolt is pressed forward to engage with the stops or catches a a. The stops or catches a a a are fastened

to the window frame or jamb E in any suitable manner, and the number will be varied to suit the size of the window.

50 The case A is provided with V-shaped grooves, (shown by e e' e''), with which the lever or thumb-piece C engages.

K K are the projections which form the V-shaped grooves.

55 F shows the attachment of the thumb-piece to the bolt.

c c are lugs, which keep the thumb-piece from striking back against the window-sash.

L shows the hole for the reception of the 60 bolt.

When I use my invention to lock the window in any required position, I use the stops or catches a a a in pairs, as shown by a a in Fig. 1, and when it is used merely as a stop 65 single catches are used. The support for these catches is shown in the drawings by D, it being made of any suitable material.

The operation of my invention is as follows: The window being closed, the bolt is turned 70 by lever C into the position shown by Fig. 3, the window-sash is raised, and the beveled groove J of the bolt G will drive the bolt back, so that it will readily pass by the catches a a a and rest on the top of any one of 75 them, as shown in Fig. 3. By reversing the bolt, as shown in Fig. 6, the beveled groove J will come in contact with the upper side of the catches, driving the bolt back, so that it will readily pass by and lock the window 80 when the lower catch is passed.

When my invention is used as a lock to lock the window in any required position, the end of the bolt is brought to a position between the two catches a a, (shown in Fig. 1,) 85 and then turned so that the lever C rests in the middle groove, c', where it is held, and the beveled part of the bolt being turned so that it is not in contact with either the upper or lower catch, the bolt locks the window-sash, as shown in Fig. 1. By this arrangement the window-sash is locked between any two of the series of catches a a, and secures the window at any desired point.

Having thus described my invention, what I claim to have invented, and desire to secure by Letters Patent, is—

1. In a window-sash stop and lock, the bolt G, provided with the beveled groove J, in combination with the pair of stops or catches a a, for stopping and locking the sash, substantially as described.
2. The case A, provided with the V-shaped

grooves or notches e e' e'', constructed, as shown, to retain the bolt in the desired position, in combination with the bolt G, provided with the lever C, the spring M, and the catch a, all substantially as described.

EDWARD S. CORY.
